UNITED STATES PATENT OFFICE.

LEONARD L. ZACHARIAS, OF WICHITA, KANSAS.

AUTOMOBILE-SIGNAL.

1,245,853.

Specification of Letters Patent. Patented Nov. 6, 1917.

Application filed August 4, 1916. Serial No. 113,156.

To all whom it may concern:

Be it known that I, LEONARD L. ZACHARIAS, a citizen of the United States, residing at Wichita, in the county of Sedgwick and State of Kansas, have invented a new and useful Automobile-Signal, of which the following is a specification.

This invention relates to signals for use in connection with automobiles whereby warning may be given to a vehicle following an automobile or to pedestrians whenever said automobile is about to turn in either direction or to come to a stop.

One of the objects of the invention is to provide a signal adapted to be placed at each side of or be built into the vehicle and which can be operated from the steering wheel or other convenient place, it being possible to shift either or both of the signals out of their normal positions where they will be visible to drivers of vehicles in the front and rear thereof and to pedestrians.

A still further object is to provide electrically operated means of novel form for shifting the signal to active position.

Another object is to provide a signal apparatus which can be readily applied to the wind shield or other part of a vehicle or can be built into the vehicle and which is simple and compact in construction and does not detract from the appearance of the vehicle.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a vertical section through the housing of the signal, the signal arm being shown in full lines in active or raised position and in dotted lines in its normal or lowered position and the electrical connections being shown diagrammatically.

Fig. 2 is a perspective view of the signal apparatus.

Referring to the figures by characters of reference 1 designates a base plate adapted to be fastened in any suitable manner to a wind shield or other part of a vehicle, this plate being provided with a cap 2 forming a housing and which cap has a slot 3 extending within one side and a portion of the bottom thereof.

Arranged within the cap and extending from the base plate 1 is a stud 4 on which a signal arm 5 is mounted, this arm projecting through the slot 3 and being adapted to swing within said slot from a vertical to a horizontal position and vice versa. The hub portion 6 of the signal arm has a segmental armature 7 fixed relative thereto and this armature carries a contact 7' designed, during the movement of the armature through 90 degrees, to successively engage arcuate contact plates 8, 9 and 10 mounted on an insulating strip 11 or otherwise suitably insulated from each other. Arranged adjacent the contact plates are radially disposed magnets 11', 12 and 13, the magnet 11' being electrically connected to the contact strip 8, the magnet 12 being electrically connected to the contact strip 9, and the magnet 13 being electrically connected to the contact strip 10. The several magnets are preferably supported by a bowed strip 14 mounted on the base 1 and which holds the magnets radially disposed relative to the stud 4. The several magnets are electrically connected to a switch 15 which, in turn, is electrically connected to a source of electrical energy indicated at 16 and the source is connected to the base 1.

The switch 15 may be in the form of a push button mounted on the steering wheel of the vehicle or some other place where it can be conveniently reached. A small lamp 17 may be arranged upon the outer portion of the arm 5 and this lamp is preferably designed to give a red light. The lamp may be electrically connected in any suitable manner with a source of electrical energy.

When the signal is used in connection with an automobile or the like, the same is connected to one side of the wind shield or other portion of the vehicle or is built into the vehicle. Preferably a pair of the signals is used, one being arranged at each side of the vehicle. Each signal is provided with an individual switch 15.

Under normal conditions, the arm 5 of each signal hangs downwardly close to the

side of the vehicle and the segmental armature 7 is supported against a stop or buffer 18 on the base 1 and partly in the field of the magnet 11. When the armature is thus 5 located the contact 7' engages the contact strip 8.

When it is desired to shift the arm 5 to raised or active position, the operator closes the switch 15. Thus a circuit will be established from the source 16 through base 1 and stud 4 to the segmental armature 7 and thence through contact 7' and strip 8 to the magnet 11'. When the magnet is thus energized it will shift the armature 7 out of its 10 normal position, thereby bringing the contact 7' into engagement with strip 9 whereupon the magnet 12 will be energized and the armature will be drawn into the field of said magnet. This will result in the contact 7' coming into engagement with the strip 10 whereupon the third magnet 13 will be energized and the segmental armature 7 brought to the position indicated by full lines in Fig. 1. Thus the arm 5 will 15 be brought to and maintained in active or horizontal position. If the arm at the left side of the machine is raised in this manner it will indicate to the driver of a vehicle in rear of the one to which the signal is applied and to drivers and pedestrians in front of the machine that a turn is to be made to the left. Should the arm at the 20 right of the vehicle be raised it will indicate that a turn is to be made to the right. 25 Should both arms be raised by closing both of the switches 15, it would indicate that the vehicle is to be brought to a stop. As soon as the circuit is broken by opening switch 15 the arm 5 will gravitate to its normal 30 position, indicated by dotted lines.

The cap 2 can be attached to the base 1 in any suitable manner. In the construction shown it is held in place by a screw 19 en-

gaging the stud 4 and by additional screws 20 extending into the base. These screws 45 20 can also be used as a means for attaching the base 1 to the vehicle.

The contact 7' can be in the form of a spring pressed pin carried by the armature 7 and yieldingly engaging the strip 8, 9 or 10 adjacent thereto.

The lamp 17 will indicate at night the position of the arm 5.

What is claimed is:—

A signal embodying an oscillatory signal arm, an armature movable therewith, an arcuate series of electromagnets for attracting said armature in succession to swing the arm from one position to another, an arcuate series of contacts, one for each electromagnet, a contact movable with said arm and armature and engageable with said series of contacts in succession, and a source of electrical energy connected to said electromagnets and having one pole connected to 55 said series of contacts and its other pole connected to the last mentioned contact, the contacts being so arranged that when the last mentioned contact engages any contact of said series, the corresponding electromagnet immediately in advance of the armature will be connected in circuit with the source of electrical energy to attract said armature, and in order that the last mentioned contact in moving with the armature 70 toward the respective energized electromagnet will be brought into engagement with the next contact of the series to continue the movement of said arm and armature.

In testimony that I claim the foregoing as my own, I have hereto affixed my signature in the presence of two witnesses.

LEONARD L. ZACHARIAS.
